UNITED STATES PATENT OFFICE.

WILLIAM W. GRIGSBY, OF WINNFIELD, LOUISIANA.

FORK FOR SLING-SHOTS.

1,207,025.

Specification of Letters Patent. Patented Dec. 5, 1916.

Application filed March 3, 1916. Serial No. 81,909.

To all whom it may concern:

Be it known that I, WILLIAM W. GRIGSBY, a citizen of the United States, residing at Winnfield, in the parish of Winn and State 5 of Louisiana, have invented a new and useful Fork for Sling-Shots, of which the following is a specification.

The present invention appertains to sling shots or toy catapults, and aims to provide 10 a novel and improved fork or handle for the rubbers or elastics.

This invention contemplates the provision of a fork or handle of the nature indicated, having unique means for holding or 15 clamping the rubbers or elastics, whereby they will not become accidentally detached from the fork or handle, and whereby the rubbers or elastics may be drawn to either side of the fork or handle without injuring 20 them, or impairing the operation of the sling or catapult.

It is also within the scope of the invention, to provide a fork or handle for sling shots which will be comparatively simple, 25 substantial and inexpensive in construction, and which will be convenient, practical and efficient in its use.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, can be made within the scope of what is claimed, without departing from the spirit of the invention.

The invention has been illustrated in several 40 of its embodiments in the accompanying drawing, wherein:

Figure 1 is a perspective view of the one piece form of the invention. Fig. 2 is a similar view of a two part form of the invention. Fig. 3 is a similar view of another 45 variation embodying two members. Fig. 4 is a sectional detail on the line 4-4 of Fig. 3. Fig. 5 is a perspective view of still another modification, wherein the fork or handle embodies three parts.

Referring specifically to Fig. 1, wherein 50 the handle or fork is constructed from a single blank of sheet metal or other suitable material, the same embodies a doubled handle 1, each section of leaf of which is provided at its free end with a crotch portion 2. The crotch portions 2 are disposed adjacent

each other, and have the free ends of their arms reflexed or bent back adjacent each other, as at 3. Bolts or clamping members 4 are engaged through the arms of the 60 crotch portions 2 adjacent the reflexed ends 3, whereby the reflexed ends may be clamped together to grip the ends of the rubbers or elastics 5 therebetween. In this manner, the ends of the rubbers or elastics 5 may be 65 readily and effectively attached to the ends of the branches of the fork or handle, without danger of the rubbers becoming accidentally detached, and furthermore, the rubbers or elastics may operate effectively 70 from either side of the fork for projecting the missile or projectile.

In the form of the invention illustrated in Fig. 2, the handle or fork comprises two parts, which may be stamped or formed 75 from sheet metal or other suitable material. This form of the fork embodies the handle 1^a having the crotch portion 2^a whose arms have their free ends reflexed or bent back, as at 3^a. An arcuate or U-shaped crotch portion 2^b is disposed adjacent and complements the crotch portion 2^a, and has its end portions reflexed or bent back, as at 3^b, adjacent the reflexed ends 3^a. Clamping bolts or elements 4^a are engaged through the arms 80 of the crotch portions 2^a and 2^b for clamping the rubbers between the reflexed end portions 3^a and 3^b.

The two part handle or fork illustrated in Fig. 3, embodies the handle sections 1^c which are curved transversely to provide a curved handle, and which have the crotch portions 2^c at their upper ends. The arms or branches of the crotch portions 2^c have their free ends reflexed adjacent each other, as 90 at 3^c, whereby when the bolts 4^c engaged through the said arms or branches adjacent the reflexed ends 3^c, are tightened, the rubbers or elastics may be clamped between the said reflexed ends, as above indicated. In 95 this form, the lower end of one handle section 1^c is engaged within the lower end of the other handle section, as illustrated in Fig. 4, to render the handle rigid.

In the modification illustrated in Fig. 5, 105 a three piece fork is illustrated, which embodies the handle 1^d having the crotch portion 2^d whose terminals are reflexed as at 3^d. A pair of strips or pieces 2^e coöperate with the arms or branches of the crotch portion 110 2^d, and have the reflexed ends 3^e coöoperating with the reflexed ends 3^d, whereby the

clamping bolts 4^a engaged through the arms of the crotch portion 2^a and through the pieces 2^e, may be tightened to clamp the rubbers or elastics between the reflexed ends 5 3^a and 3^e.

From the foregoing, taken in connection with the drawing, it will be evident that the several forms of the invention have common advantages, as well as independent ones, due 10 to their common and varied details, respectively, and it being noted that in each form of the invention, the arms or branches of the crotch each embody two parts at opposite sides of a common median plane for 15 receiving a rubber or elastic therebetween and having the reflexed ends, and a clamping bolt or element engaged through the said parts adjacent the reflexed ends. The advantages and uses of the present sling 20 shots or toy catapults will be obvious from the foregoing, taken in connection with the drawing.

Having thus described the invention, what is claimed as new is:—

25 1. A catapult fork embodying a pair of crotch portions disposed side by side and adapted to clamp rubbers or elastics between

their ends, and means for clamping said portions together.

2. A catapult fork having a crotch portion, each arm of which embodies two parts having coöperating reflexed ends for receiving a rubber or elastic therebetween, and a clamping element engaged through the parts of each arm adjacent the said reflexed ends. 35

3. A catapult device having an arm composed of two parts having coöperating reflexed ends for receiving a rubber or an elastic therebetween, and means for clamping said parts together adjacent said ends. 40

4. A catapult fork embodying a pair of crotch portions disposed side by side and having their ends formed to clamp rubbers or elastics therebetween, and clamping elements connecting said portions adjacent the 45 ends thereof.

In testimony that I claim the foregoing as my own, I have hereto affixed my signature in the presence of two witnesses.

WILLIAM W. GRIGSBY.
